UNITED STATES PATENT OFFICE.

WILLIAM H. DORSEY, OF NEW BRIGHTON, NEW YORK, ASSIGNOR, BY MESNE ASSIGNMENTS, TO PROSPERITY COMPANY, INC., OF SYRACUSE, NEW YORK, A CORPORATION OF NEW YORK.

GARMENT PRESS.

Application filed September 10, 1924. Serial No. 736,865.

This invention relates to garment pressing machines and particularly to improvements directed to the comfort and convenience of the operator to afford more healthful and pleasant working environments; and an object is to improve upon the construction shown in the Palmer Patent 1,319,108.

An object of the invention is to produce garment press and particularly ironing press improvements whereby the heat and vapor arising from the work are blown rearwardly away from the operator, collected by a suction device and removed from the room. Those conversant with the art have appreciation for the overly warm uncomfortable working environments and conditions existing in and about laundries and at the front of modern large jaw wide opening pressing machines which arises by virtue of rapidly ironing large-size pieces with highly heated jaws thereby releasing considerable vapor and heat on the operator; and my present invention has to do with the elimination of this discomfort and menace to the operator's health.

An additional object of the invention is to provide a garment pocket and cuff cleaner for a pressing machine whereby the same air as used for operating the vapor and heat removing apparatus may likewise be used for operating the said cleaner.

The accompanying drawing shows one form of the invention illustrating the principles thereof, and it is to be understood that changes may be made without departing from the scope of the invention for the purpose of producing a commercial machine in accordance with the plans of this invention.

Figure 1 shows a fragmentary top view of a press embodying my improvements; and Figure 2 shows a side view thereof.

Referring further to the drawings for a detailed description of the invention, there is shown a press frame 10 supporting a buck 11. A press lever 12 is pivoted at 11 on the frame 10, and the rear end of this lever is fitted with any suitable form of link, toggle, or lever operating means 13 by which the said lever 12 is rocked on the fulcrum point 11 to raise and lower a press head 14 anchored to the front end of said lever. The head and buck are heated by any suitable means but the heating means

and press opening and closing leverage is omitted for clearance in illustrating my particular improvements because those features are not essential to an understanding of this invention.

One of the pressing members is chosen for illustrating the principle and construction of this invention and though the air blowing system may be adapted to either one or both pressing jaw members, I have illustrated my improvements as attached to the head 14. The head 14 is made with an air passage 16 extending along the front margin of the head, and this passage is provided with an air discharge orifice or row of perforations 17 by which air is discharged under pressure from the passage 16. The discharge orifice 17 is preferably directed at an angle rearwardly and downwardly so as to strike the work on the pressing surface of the buck 11; and as the head 14 rises, the air discharge from the orifice 17 vigorously expels all the heat and vapor as generated between the hot press jaws. The passage 16 is integrally joined with a passage 18 extending rearwardly across the upper face of the head and this passage may have its rear end tapped and drilled for connection with a pipe 19. The rear end of the pipe 19 connects with a pivotal air joint 20 by which compressed air is delivered to the movable jaw, as will now be described.

A hollow air joint or arm 20 has its front end screw threaded into the pipe 19 and the other end is made with a stuffing box body 21, and a packing gland nut 22 is screwed onto the body 21 by which the said hollow air arm 20 is made to movably and pivotally connect with a main air supply pipe line 23. The rear end of the hollow pivotal air arm 20 carries an integral disc 24 and cam 28 as a means of automatically operating an air control valve as later explained.

A valve 25 is included in the air pipe line 23 and this valve is equipped, for illustration purposes, with an offset valve body 26 which is provided with a valve stem 27 normally closed by a spring which continuously maintains the valve 25-26 in closed position thereby stopping the flow of air upwardly through the pipe 23. The cam 28 is disposed in alignment with the stem 27 to ride upon the stem and thrust it downwardly thereby opening the valve

25—26 when the head 14 rises, but when the head reaches upwardly or downwardly limited position, the cam 28 slides off the valve stem 27 which permits the valve 25—26 5 to be closed.

The operation of the automatic air valve 25—26 is such that air pressure from the pipe line 23 is discharged from the orifice 17 during the up and down motion of the head 14, but this air blowing function is terminated at the end of the opening stroke and closing stroke of the pressing head. Though I may prefer to so arrange the machine that the discharge of air takes place back through the press jaws only while the head is lifting, yet at the same time I have 10 illustrated the blowing function as performing during both up and down head movements.

20 Any suitable means is provided for supplying air under pressure to the main pipe line 23. In the present instance a motor 30 drives a pump or a blower 31 and the pipe 23 is connected to the blower. Those conversant with the art will readily understand how a battery of pressing machines equipped with the vapor and heat remover may be supplied with air from a single and common source of supply, and one motor and 25 fan may be employed to operate a plurality of machines.

It is desirable to entirely remove the heat and vapor from the room and region of the 30 pressing machine and to this end a hood-like receptacle or air and vapor receiver 33 is placed to the rear of the pressing machine jaws and connects with a suction fan 35, and the said fan 35 is adapted to discharge the heat and vapor outwardly 35 through a pipe 36 and outside the room or establishment in which one or more presses are located. The fan 35 is driven by the motor 30. The pressing machine table 37 is sometimes constructed from sheet metal 40 and may therefore be shaped up to form the hood 33 at the rear of the press. The same motor 30 is arranged to drive the blower 31 and the exhauster 35. The velocity of the blast of air issuing from the orifice 17 45 sweeps the heat and vapor from the jaws directly back into the hood 33 and thus the working environments of the press are maintained in a cool and healthful condition.

An operator in a laundry works more 50 efficiently and is not physically exhausted by the ill-smelling vapors and heat arising from freshly ironed wash goods when the press is equipped with the features of my invention; and furthermore all disagreeable odor 55 and heat are removed from the room which is not true of other pressing machines in use or suggested.

A garment pocket and cuff cleaning device 40 is mounted on the table of the pressing 60 machine and is connected through a pipe 41

to the air supply pump or fan 30. The pipe 41 is equipped with a suitable hand controlled valve 42 which stops and starts the air supply through the air blowing device 40. This pocket and cuff cleaner comprises 70 a hollow spreading fan-shaped instrument 40 having scratcher or dirt loosening teeth 42. The body 40 and teeth 42 are hollow, the said parts 42 constituting in fact nozzles for setting up high velocity air streams capable 75 of entering the crevices and seams of pockets and cuffs for blowing out dirt from cuffs and pockets. The spread of the hollow air blowing body 40 causes the instrument to reach a large area to be cleaned; and this pocket and cuff cleaner is especially useful for pressing machines because the tailor has conveniently available a ready useful cleaning device which he may use 80 without the loss of time before or after pressing a garment.

It is to be understood that the heat and vapor remover system described in connection with a pressing machine is more especially useful on ironing and laundry presses, and that ironing presses do not necessarily require the pocket and cuff cleaner for ironing machines are used on wash goods. On the other hand, the pocket and cuff cleaner 85 is more particularly useful in connection with garment presses used by tailors for pressing suits and other garments whereas it is not necessarily intended for extensive use with ironing presses. However, I have illustrated both improvements and new uses for air in connection with one and the same machine.

What I claim is:—

1. A garment pressing machine comprising 90 cooperating press jaws one of which is provided with an air discharge orifice along the margin thereof, an air pipe to supply air pressure to the orifice by which the vapor and heat ordinarily arising from the work are blown away from the operator, a valve included in the air pipe, and means for automatically operating the valve to control the flow of air pressure when the press opens and closes.

2. A garment pressing machine comprising 95 cooperating press jaws and means to open and close the same and one jaw being provided with an air discharge orifice along the margin thereof, means to supply air pressure to the orifice by which the vapor and heat ordinarily arising from the work are blown away from the operator, automatic valve control means to cause the air to blow only during the opening and closing motion of the press, a hood-like funnel air receiver in line with the press jaws, and suction means connected with the receiver.

3. A pressing machine comprising in combination, cooperating press jaws and means 100 to open and close the press, an air duct in- 105

- tegrally formed along the front margin of one press jaw, another duct integral with the first one named and leading rearwardly, an air arm having one end attached to the 5 last named duct and means to rotate the arm as the press opens and closes, an air supply pipe pivotally connected with the other end of the air arm, a cam carried on the arm and rotatable therewith, and a valve in the air 10 supply pipe including means to open and close it by the cam.
4. A pressing machine comprising in combination, a frame, press jaws one of which is movable and a press lever fulcrumed on 15 the frame and connected to the movable jaw to open and close the press, an air passage and discharge orifice made in the movable pressing member, an air arm pivoted at the fulcrum point of the lever and connected with the air passage and orifice, an air 20 supply pipe line connected with the arm, a valve disposed in the pipe line, and a cam journaled coaxially with the lever fulcrum movable with the jaw and cooperating with the valve to open and close the air pipe line. 25
5. A press comprising jaws and means to open and close the press including a pivoted press lever; fluid spraying means included in one of the jaws and a pipe line to convey 30 fluid to the jaw, a valve in the pipe, and operating means concentric with the press lever pivot to actuate the valve when the press opens and closes.

In testimony whereof I affix my signature.

WILLIAM H. DORSEY.
